UNITED STATES PATENT OFFICE

125,597

DESIGN FOR A SUIT

Bruno Staehle, New York, N. Y.

Application October 19, 1940, Serial No. 95,947

Term of patent 3½ years

To all whom it may concern:

Be it known that I, Bruno Staehle, a citizen of the United States, residing at 25 Central Park West, New York city, in the county of New York and State of New York, have invented a new, original, and ornamental Design for a Suit, of which the following is a specification, reference being had to the accompanying drawing, forming part thereof.

The back of the skirt is plain.

I claim:

The ornamental design for a suit, substantially as shown and described.

BRUNO STAEHLE.
